UNITED STATES PATENT OFFICE

EDWARD E. STEVENSON, OF LOS ANGELES, CALIFORNIA, ASSIGNOR TO EMSCO DERRICK & EQUIPMENT COMPANY, OF LOS ANGELES, CALIFORNIA, A CORPORATION OF CALIFORNIA

EXPANDING MANDREL

Application filed January 19, 1929. Serial No. 333,565.

My invention relates to mandrels, and in its preferred embodiment it consists of a mandrel for aligning liners in the jacket of an oil pump barrel.

5 One of the features of the mandrel of my invention is that part of the liners (or members to be held thereby) may be placed on and secured to the mandrel and afterwards one or more additional liners (or equivalent members) may be placed thereon and clamped in place.

This design of mandrel is especially desirable for aligning liners of the character shown in my copending application entitled 15 Method of placing liners in a sleeve for deep well oil pumps, Serial No. 302,230, filed August 27, 1928. In the pump barrel of that application the end liners have enlargements which prevent them from being extended 20 through the pump jacket or sleeve. The disadvantage of the usual type of mandrel when used on this type of pump is that the liners cannot be clamped in position by expanding the mandrel until after the mandrel and liner 25 assembly have been passed into the jacket and the other end liner placed thereon.

One of the end liners, because of its enlargement, must be placed on the mandrel after the other liners and the mandrel have 30 been inserted in the jacket. If the mandrel were tightened before all the liners were assembled thereon, as would occur if it were expanded before the assembly was inserted in the jacket, the mandrel would be ruined 35 since all the expansion would be in the end where there was no liner.

My invention overcomes these objections by providing a mandrel in which a plurality of liners may be clamped thereon without injury to the mandrel, and other liners may 40 afterward be placed on the mandrel next to the first liners and clamped in place.

Other objects and advantages of my invention will be evidenced in the following detailed description of my invention.

Referring to the accompanying drawing: Fig. 1 is an elevational view in section showing the utility of the invention.

Fig. 2 and Fig. 3 are sectional views of the invention.

Fig. 4 and Fig. 5 are sections taken on the corresponding lines of Figs. 2 and 3.

Referring to the drawing, 11 is a support consisting of a primary support-rod 12 and a secondary support-rod 14. The support- 55 rods 12 and 14 are threaded on their near ends so that they may be screwed into a threaded opening 15 of an abutment 16. The abutment 16 has a medial shoulder 17 having beveled end faces 18; and it has cylindrical centralizing portions 19 which are of smaller diameter than the shoulder 17.

Surrounding the primary support-rod 12 is a primary expandable means 20 which will now be described.

Surrounding the support-rod 12 is a distance sleeve 21, the lower end of which surrounds and is centralized by the upper centralizing shoulder 19. The lower end of this distance sleeve 21 is beveled and engages the upper bevel face 18 of the shoulder 17. The upper end of the distance sleeve is centralized by a ring 22 which is secured to the distance sleeve and engages the primary support-rod 12. The upper end of the distance sleeve has an externally beveled end face 23.

Surrounding the primary support-rod 12 above the distance sleeve 21 are intermediate primary expandable sleeves 25 and an end primary expandable sleeve 26. The intermediate and end expandable sleeves are rendered 75 expandable at their lower ends by slits 27 which form strips 28.

The lower ends are internally beveled so that the lower ends of the strips 28 have beveled ends 29. The upper ends of the intermediate primary expandable sleeves 25 are provided with externally beveled ends 30. The beveled ends 29 of the lower intermediate primary expandable sleeve engage the beveled end of the distance sleeve 21; the beveled ends 29 of the upper intermediate primary expandable sleeve engage the upper beveled end 30 of the lower expandable sleeve; and the lower beveled ends 29 of the end primary expandable sleeve 26 engage the upper beveled end 30 of the upper intermediate primary expandable sleeve 25. The upper ends of the intermediate sleeves 25 are centralized by rings 33 which are secured 95 to the intermediate sleeves 25.

thereto, and which engage the primary support-rod 12. The lower ends of the intermediate sleeves 25 are centralized by rings 34 which are inserted into a position adjacent to the strips 28 and which engage the primary support-rod 12.

The upper end of the end primary expandible sleeve 26 has internal threads 36 which receive a threaded end 37 of a collar 38. The 10 collar 38 has a cylindrical opening 39 through which the primary support-rod 12 extends for centralizing the collar 38. For the purpose of expanding the primary expandible means I provide the following described 15 means. The upper end of the primary support-rod 12 has threads 40 and a nut 41 is screwed thereon. By screwing the nut 41 downward on the primary support-rod 12, the collar 38 moves the end primary expandible member 26 downward so that the lower beveled ends 29 on the strips 28 are expanded.

The end primary expandible member 26 likewise forces the intermediate expandible primary members 25 downward causing the 25 strips 28 of these members to be expanded due to the engagement of the lower beveled ends 29 thereof and the upper beveled ends 30.

Below the abutment 16 is a secondary expandible means 45, which will now be described.

Surrounding the secondary support-rod 14 is an upper expandible sleeve 46. The upper end of the sleeve 46 surrounds lower centralizing means 12^a, and a beveled end 47 of the sleeve 46 engages the lower beveled face 18 of the abutment 16. The lower end of the upper secondary expandible sleeve 46 is provided with slits 48 which form strips 49. The lower ends of the strips 49 are provided in the form of internally beveled ends 50. The extreme upper end of the sleeve 46 is centralized by the centralizing means 12^a, as previously pointed out, and this sleeve 46 is 45 further centralized by the centralizing ring 52 which is secured in the sleeve 46 and contacts the secondary support-rod 14.

Arranged on the support-rod below the sleeve 46 is a lower secondary expandible sleeve 53. The upper end of the sleeve 53 is provided with an externally beveled face 54 adapted to be engaged by the beveled ends 50 of the strips 49. The lower end of the sleeve 53 is provided with slits 55 which form strips 56 similar to the strips 49 and also 55 similar to the strips 28 of the primary expandible means.

The upper end of the sleeve 53 is centralized by a centralizing ring 58 which is forced 60 into the upper end of this sleeve, and which contacts the secondary support-rod 14. The lower end of the sleeve 53 is centralized directly above the strips 56 by means of a centralizing ring 59 which is secured in the sleeve 65 53 and which contacts the secondary support-

rod 14. Placed on the lower end of the support-rod 14 is an expander member 61 having a cylindrical centralizing portion 62 and an externally beveled face 63 which is adapted to be engaged by internally beveled end faces 64 provided at the lower ends of the strips 56. The expander member has an opening 67 through which the secondary support-rod 14 is extended for holding this part 61 concentric.

For the purpose of expanding the secondary expandible means I provide a secondary expanding means which I shall now describe. This secondary expanding means is in the form of a nut 69 having a body 70, and a polygonal head 71. The body 70 is provided with a cavity which is threaded at 72, and into which a lower threaded end 73 of the secondary support-rod 14 is screwed. By turning the nut 69 so that it is advanced upward on the secondary support-rod 14, the expander member 61 and the lower secondary expandible sleeve 53 are moved upward so that the strips 49 and 56 are expanded.

The important part of the invention is, as has been already pointed out, that the primary expandible means and the secondary expandible means may be individually operated, one not affecting the operation of the other. One of the important considerations 95 is the central abutment 16 which permits both of the expandible means to be forced toward this abutment and to be expanded.

In Fig. 1 the utility of my invention is illustrated. In this figure the numeral 75 represents the jacket of an oil well pump and the numeral 76 represents an upper collar which has been screwed into the upper threaded end of the jacket. The numeral 77 represents an end liner having an enlargement 78 at the upper end thereof which prevents it from being extended through the jacket 75. The numeral 79 represents intermediate liners which have cylindrical inner and outer surfaces which do not interfere with its being extended through the jacket 75. Both of the end liners of the pump have enlargements 78; consequently it is impossible to completely assemble the liners before they are installed on the mandrel and consequently it is necessary to place one of the end liners on the mandrel after it has been extended into the jacket 75. In Fig. 1 all of the liners except the lower end liner have been placed on the mandrel. The primary expandible means has been expanded so that the liners which have been assembled thereon are rigidly held in alignment.

This expansion is accomplished by screwing the primary nut 41 downwardly on the primary support-rod 12 as already pointed out. After the parts have been clamped in alignment, and have been inserted into the jacket 75 as shown in Fig. 1, the upper collar 38 may be screwed into place. The lower 130

end liner 77 is then installed in place as indicated by dotted lines 81. The secondary expansible means is then expanded by screwing the secondary nut 69 upward on the secondary support-rod 14.

It will be noted that the lower end of the lowest intermediate liner 79 terminates about midway of the strips 49. When the end liner 77 is installed in place and the secondary expansible means is expanded, these strips 49 centralize the lower end of the lower intermediate liner 79 and the upper end of the lower end liner 77. The lower end of the lower end liner 77 is centralized by the strips

- 10 56. After the entire liner has been centralized and rigidly clamped on to the mandrel as just described, the lower collar, not shown, which is identical with the collar 38, is secured in place so that the liners are all rigidly 20 clamped together. The primary and secondary expansible means is then released, and the mandrel is removed from the pump barrel.

I claim as my invention:

1. In an expanding mandrel, the combination of: a support; an independently operable primary expansible means on said support; an independently operable secondary expansible means on said support; primary expanding means for expanding said primary expansible means; and secondary expanding means operable independently of said primary means for expanding said secondary expansible means.

2. In an expanding mandrel, the combination of: a support; an abutment carried by said support; primary expansible means carried by said support; primary expanding means for moving said primary expansible means toward said abutment in order to expand same; secondary expansible means carried by said support; and secondary expanding means for moving said secondary expansible means toward said abutment for expanding said secondary expansible means.

3. In an expanding mandrel, the combination of: a support-rod; an abutment rigidly secured to said rod; a primary expansible sleeve surrounding said rod and engaging said abutment; a secondary expansible sleeve surrounding said rod and engaging said abutment; primary expanding means for expanding said primary expansible sleeve; and secondary expanding means for expanding said secondary expansible sleeve.

4. In an expanding mandrel, the combination of: a support-rod; an abutment rigidly secured to said rod; a primary expansible sleeve surrounding said rod and engaging said abutment, said primary expansible sleeve being expansible remote from said abutment; a secondary expansible sleeve surrounding said rod and engaging said abutment; primary expanding means for expanding said primary expansible sleeve; and sec-

ondary expanding means for expanding said secondary expansible sleeve.

5. In an expansible mandrel, the combination of: a support-rod; an abutment rigidly secured to said rod; a primary expansible sleeve surrounding said rod and engaging said abutment; a secondary expansible sleeve surrounding said rod and engaging said abutment, the end of said secondary sleeve remote from said abutment being expansible; primary expanding means for expanding said primary expansible sleeve; and secondary expanding means for expanding said secondary expansible sleeve.

6. In an expansible mandrel, the combination of: a support-rod; an abutment rigidly secured to said rod; a primary expansible sleeve surrounding said rod and engaging said abutment, said primary expansible sleeve being expansible remote from said abutment; a secondary expansible sleeve surrounding said rod and engaging said abutment, the end of said secondary sleeve remote from said abutment being expansible; primary expanding means for expanding said primary expansible sleeve; and secondary expanding means for expanding said secondary expansible sleeve.

7. In an expansible mandrel, the combination of: a support-rod; an abutment rigidly secured to said rod; a primary expansible sleeve surrounding said rod and engaging said abutment; a secondary expansible sleeve surrounding said rod and engaging said abutment; centralizing means at said abutment for centralizing adjacent ends of said primary expansible sleeve and said secondary expansible sleeve; primary expanding means for expanding said primary expansible sleeve; and secondary expanding means for expanding said secondary expansible sleeve.

8. In an expansible mandrel, the combination of: a support-rod; an abutment rigidly secured to said rod; a primary expansible sleeve surrounding said rod and engaging said abutment, said primary expansible sleeve being expansible remote from said abutment; a secondary expansible sleeve surrounding said rod and engaging said abutment; centralizing means at said abutment for centralizing adjacent ends of said primary expansible sleeve and said secondary expansible sleeve; primary expanding means for expanding said primary expansible sleeve; and secondary expanding means for expanding said secondary expansible sleeve.

9. In an expansible mandrel, the combination of: a support-rod; an abutment rigidly secured to said rod; a primary expansible sleeve surrounding said rod and engaging said abutment; a secondary expansible sleeve surrounding said rod and engaging said abutment, the end of said secondary sleeve remote from said abutment being expansible; centralizing means at said abut-

ment for centralizing adjacent ends of said primary expandible sleeve and said secondary expandible sleeve; primary expanding means for expanding said primary expandible sleeve; and secondary expanding means for expanding said secondary expandible sleeve.

10. In an expandible mandrel, the combination of: a support-rod; an abutment rigidly secured to said rod; a primary expandible sleeve surrounding said rod and engaging said abutment, said primary expandible sleeve being expandible remote from said abutment; a secondary expandible sleeve surrounding said rod and engaging said abutment, the end of said secondary sleeve remote from said abutment being expandible; centralizing means at said abutment for centralizing adjacent ends of said primary expandible sleeve and said secondary expandible sleeve; primary expanding means for expanding said primary expandible sleeve; and secondary expanding means for expanding said secondary expandible sleeve.

11. In an expandible mandrel, the combination of: a support-rod; an abutment rigidly secured to said rod; a primary expandible sleeve surrounding said rod and engaging said abutment, said primary expandible sleeve including a distance sleeve adjacent 20 to said abutment; a secondary expandible sleeve surrounding said rod and engaging said abutment; primary expanding means for expanding said primary expandible sleeve; and secondary expanding means for 25 expanding said secondary expandible sleeve.

In testimony whereof, I have hereunto set my hand at Los Angeles, California, this 10th day of January, 1929.

EDWARD E. STEVENSON.
